D. STEC

Des. 166,889

WALL PLAQUE

Filed Oct. 31, 1951

INVENTOR.

Dmytro Stec

UNITED STATES PATENT OFFICE

166,889

WALL PLAQUE

Dmytro Stec, Dearborn, Mich.

Application October 31, 1951, Serial No. 17,177

Term of patent 7 years

(Cl. D29—23)

To all whom it may concern:

Be it known that I, Dmytro Stec, a citizen of the United States, residing at Dearborn, in the county of Wayne and State of Michigan, have invented a new, original, and ornamental Design for a Wall Plaque, of which the following is a specification, reference being had to the accompanying drawing, forming part thereof, in which:

Fig. 1 is a front elevational view of a wall plaque, showing my new design; and,

Fig. 2 is a side elevational view thereof.

I claim:

The ornamental design for a wall plaque, as shown.

DMYTRO STEC.
